US0D1050111S

(12) **United States Design Patent** (10) **Patent No.:** **US D1,050,111 S**
(45) **Date of Patent:** **** Nov. 5, 2024**

(54) **WEARABLE DEVICE**

(71) Applicant: **Sempulse Corporation**, San Marcos, TX (US)

(72) Inventor: **Kurt Stump**, San Diego, CA (US)

(**) Term: **15 Years**

(21) Appl. No.: **29/798,302**

(22) Filed: **Jul. 7, 2021**

(51) **LOC (14) Cl.** **14-02**

(52) **U.S. Cl.**

USPC **D14/344**

(58) **Field of Classification Search**

(57)

CLAIM

The ornamental design for a wearable device as shown and described.

DESCRIPTION

FIG. 1 is a perspective view of a wearable device in a first orientation;

FIG. 2 is a top view of a wearable device;

FIG. 3 is a bottom view of a wearable device;

FIG. 4 is a front view of a wearable device;

FIG. 5 is a rear view of a wearable device;

FIG. 6 is a left side view of a wearable device; and,

FIG. 7 is a right side view of a wearable device.

The broken lines in the drawings form no part of the design to be patented.
